(57) **CLAIM**

The ornamental design for a monocular grip, as shown and described.

DESCRIPTION

FIG. 1 is a top-front perspective view of a monocular grip showing my new design;

FIG. 2 is a bottom-rear perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof; and,

FIG. 8 is a bottom plan view thereof.

The broken lines shown in FIGS. 1-8 show an eye piece, an adjustment knob, a front face, and a strap attachment knob that form no part of the claimed design.

1 Claim, 8 Drawing Sheets

FIG. 3

FIG. 4

FIG. 5

FIG. 6

FIG. 7

FIG. 8
